UNITED STATES PATENT OFFICE.

JOHN ANDERSON, OF HAMILTON, ONTARIO, CANADA, ASSIGNOR TO ALLITH MANUFACTURING COMPANY, OF HAMILTON, CANADA.

SUPPORT FOR SLIDING-DOOR TRACKS.

No. 897,697.

Specification of Letters Patent.

Patented Sept. 1, 1908.

Application filed September 11, 1907. Serial No. 392,373.

To all whom it may concern:

Be it known that I, JOHN ANDERSON, a citizen of the Dominion of Canada, and residing at No. 99 Bay street N., in the city of 5 Hamilton, in the county of Wentworth, in the Province of Ontario, Canada, have invented a new and useful Support for Sliding-Door Tracks; and I do hereby declare that the following is a full, clear, and exact description 10 of the construction and operation of the same.

The invention relates to a very convenient device for supporting sliding door tracks, which possesses the advantages of not being required to be riveted to the track, does not require to be driven in the track from either end, but can be placed in the track at any desired point. It has a perfectly balanced fit in the track, and is capable of 15 sustaining greater weight of the door on account of its vertical position in the track, and other advantages as will be more fully shown hereinafter. I attain these objects by the mechanism illustrated in the accompanying drawing, in which:—

Figure 1, is a front elevation of section of a door with track attached thereto. Fig. 2, is an end view of the same somewhat enlarged. Fig. 3, is a front view of the track 30 support detached. Fig. 4, is a side view of the same. Fig. 5, is a side view of the track. Fig. 6, is a transverse section of the same. Fig. 7, is a cross section of a modification of the same.

35 In the drawing A, represents a barn door. B, the track; formed ear shaped, being larger at the top than the bottom, as clearly shown at Fig. 6, and having a horizontal opening *a*, on the inner side, as shown in Figs. 2, 5 and 6. 40 C, Figs. 3 and 4, represent front and side views respectively, of the support for the track B, which consists of an oval shaped base plate *b*, having two bolt openings *d*, *d*, at the top and a notch *e*, at the bottom for bolts *f*,

45 to pass through, by which to secure said plate to the building to be furnished therewith. Attached to the said plate C, is an ear shaped projection *g*, cast integral with it and formed with a terminal head that has 50 a rounded top and bottom one smaller than the other to correspond with the shape of the track B. The said projection is provided with a notch *h*, at the top portion and a similar one *h'*, at the bottom, into which

the bent ends 2, 3, of the track B, enter and 55 rest therein.

D, D, are brackets attached to the door A, by bolts *k*, as shown in Fig. 1, for the purpose of carrying two pulleys. The top and larger one *i*, is made to rest and run on the upper 60 portion of the track B, and the smaller one *j*, is placed so as to run under the said track B, as shown at Fig. 2.

It will be observed that the track B, while preferably made in the form shown at Fig. 6, 65 may be modified somewhat in an oval shape as shown at Fig. 7.

It will be seen that the object of forming the support C, in the shape shown at Figs. 3 and 4 is for the ease, quickness and convenience that the head *g*, can be inserted flat in 70 the opening *a*, of the track, then turned upright in the track as seen in Fig. 2, and bolted to the building to support the track. This plan has the advantage over a stationary or 75 riveted support as my track support as hereinbefore mentioned can be inserted at any point of the track B, to still further strengthen it, if there is a likelihood of its sagging, without driving the same in the track from the 80 ends as in other devices for the same purpose.

The great advantage of my device for the purpose specified is the saving of time, convenience of handling and effectiveness in operation as the supporting part *g*, is in an upright position when it supports the track, and hence can bear more weight as it is in the 85 best position for strength and durability.

I am aware that supports have been used in a tubular track, but they have to be driven 90 in from the end of the track, and have a horizontal bearing to support the track, which is objectionable as not possessing sufficient strength while my support has a vertical bearing in ear-shaped track, which is capable 95 of sustaining greater weight, is more durable, convenient and satisfactory in every particular.

Having thus described my device and its advantages, what I claim as my invention 100 and desire to secure by Letters Patent, is,—

1. The combination of a track consisting of a hollow member provided with a longitudinal slot in its rear and extending from one end thereof to the other, with a plurality of 105 supporting brackets therefor, each bracket consisting of a base, a shank extending outwardly therefrom, and a head on the outer

extremity of the shank and of less thickness than the width of the slot of the track for insertion therein and removal therefrom, the head being of such length as to interlock in the track when the bracket is turned to throw the head transversely to the slot, and the shanks of the brackets being of such length as to space the track a sufficient distance from the wall to which the track is secured for permitting a bracket to be applied to the track while the latter is in position.

10 2. A track supporting bracket comprising

a base, a shank secured to and projecting outwardly therefrom, and a head on the shank and rounded at its top and bottom, 15 said shank having recesses in its top and bottom surfaces at a point immediately adjacent the head.

Hamilton, Ontario the 23rd day of August 1907.

JOHN ANDERSON.
